UNITED STATES PATENT OFFICE.

SAMUEL KAYE, OF COLUMBUS, MISSISSIPPI.

BOTTLING-MACHINE.

1,186,481.

Specification of Letters Patent. Patented June 6, 1916.

Application filed January 28, 1908. Serial No. 412,994.

To all whom it may concern:

Be it known that I, SAMUEL KAYE, a citizen of the United States, residing at Columbus, in the county of Lowndes and State of 5 Mississippi, have invented certain new and useful Improvements in Bottling-Machines, of which the following is a specification.

My invention relates to an improvement in bottling machines.

10 The object and purpose of this machine is to fill the bottles as they are carried along on the conveyer, with carbonated water, and cap them without requiring any handling of the bottles from the time they enter the machine to the time they leave it, every part of 15 the bottling machine being wholly automatic.

With these objects in view, my present invention consists in means for feeding and 20 placing the caps; means for filling the bottles with carbonated water under pressure and disposing of the air displaced by the liquid; means for automatically turning on and shutting off the liquid; and means for 25 applying the cap and fastening it to the bottle air-tight.

My invention further consists in certain other minor details of construction and combinations of parts which will be hereinafter 30 described and pointed out in the claims.

In the accompanying drawings:—Figure 1 is a view in side elevation of my improved bottling machine, the cams 40 and 49 being omitted. Fig. 2 is a vertical section of the 35 machine, with the cams 40 and 49 omitted. Fig. 3 is a plan view of the base. Fig. 4 is an enlarged view of one of the cap pins. Fig. 5 is a side view of one of the filling heads and the means for operating it. Fig. 40 6 is a sectional view of one of the filling heads with parts broken away. Fig. 7 is a view partly in section of the cap feeding mechanism. Fig. 8 is a plan view of the cap hopper. Figs. 9 and 10 are fragmentary sectional views of the hopper. Fig. 11 shows one form of outlet for the cap feeding tube. Fig. 12 shows a modification of the form of outlet shown in Fig. 11; and Fig. 13 is a detail view to better illustrate the manner in which the rods carrying 45 the filling-heads are slidably mounted in the header.

A, represents the base of the machine and 1, 1, are uprights constituting the frame-work or superstructure, these uprights be-

ing securely bolted to the base at their lower ends. Secured to this frame are parallel overhead tracks 3 which are circular in plan, and undulating in elevation as shown in Fig. 1, parts being level or horizontal and other parts more or less abruptly inclined and irregular to accomplish certain purposes which will be hereinafter more fully described. Between these tracks the wheels 4, 4, travel, these wheels preferably being peripherally grooved as indicated at 5, 5, whereby to receive the vertical flanges of the tracks. Hangers 6, 6, depend from the axles 7, 7, of the wheels and connecting rods 8, 8, extend downwardly from a point on 70 the lower ends of these hangers immediately beneath the wheels 4, 4, through orifices 9 and 10 formed in the annular header 11 and the annular guide 12, respectively, anti-friction rollers 9^a and 10^a preferably being 75 provided to prevent friction. These connecting rods 8, 8, are provided with grooves or key-ways 13, 13, adapted to receive the splines or feathers 14 which prevent the connecting rods from turning. Each connecting rod 8 supports a filling head 15, in any approved manner, for instance as shown in Fig. 6, in which a plug 16 is screwed into the upper end of the filling head a greater or less distance whereby 80 to regulate and vary the capacity of the filling head. When thus constructed the plugs 16 are counter-bored and internally screw-threaded at their upper ends as at 17, 17, to receive the threaded lower ends of 85 the connecting rods 8, 8. This provision is made to compensate for the position of the plug within the filling head in order to maintain the desired length from the point of support to the lower end of the filling 90 head, as by turning the plug one way or the other it turns equally upon the rod and in the filling head, thus preserving the relative distance at all times between the filling head and the point of support. A lock nut 19 securely locks the plug and filling head 100 together with a packing between which prevents the escape of air or liquid through the joint thus formed. In this way, the capacity of the filling heads is not only capable of regulation, but also the length of the connecting rods remains unchanged.

The capacity of the filling heads approximately corresponds to the capacity of the bottles to be filled or is made to thus ap- 110

proximately correspond by the adjustment above described, the reason for which is readily understood, as will be explained. An air-tight joint is formed between the bottle and filling head during the filling process and there has to be some place for the air of the bottles displaced by the liquid to escape to, and as the carbonated water is discharged into the bottle under a pressure of about 30 pounds to the square inch or equivalent to two atmospheric pressures, the full volume of air contained in each filling head and bottle is thereby compressed into the filling head as the bottle becomes filled.

15 This makes room for the water as fast as the air is displaced. This brings me to the mechanism for filling the bottles with carbonated water. A header 11 is provided with an annular channel 22 and from this 20 channel as many hose 23 lead downwardly as there are filling heads, there being one hose for each filling head. Radial ducts 24 extend inwardly from the annular channel 22 and the branch pipes 25, 25, extend to 25 the inner ends of these radial ducts. There may be any number of these branch pipes 25, 25, although four would be sufficient, and they are connected at their upper ends with a swivel 26 which turns upon a fixed 30 main supply pipe 27, a stuffing box 28 being employed to form an air and water-tight joint. The pipe 27 is conveniently held in place on the frame by the set screw 29.

The lower ends of the hose are connected 35 to valve chambers 30 which latter communicate with the filling heads through threaded nipples 31. These threaded nipples are preferably bored out from each end, the inner end upon an incline, preferably, so 40 that the liquid is discharged downwardly therefrom into the mouth of the bottle which latter is adapted to be held just below the inner end of this nipple during the filling process as shown in Fig. 6. The 45 valve 32 for controlling the discharge of liquid in filling a bottle is held closed normally by means of the spiral spring 33 coiled about its stem 34, except when the bottle is in position when the valve is automatically opened. This is accomplished by 50 means of a trip lever 35 which is pivotally suspended at its upper end from the guide 12 as shown at 36, its lower end resting normally in position to be engaged and forced aside by the bottle to be filled. This trip lever is connected by means of a rod 37 to a valve operating lever 38 which latter is pivotally connected with the outer end of 55 the valve stem 34. When the trip lever 35 is pushed aside by the bottle in entering the lower end of the filling head it tilts the valve operating lever 38 into the position shown in dotted lines in Fig. 5 which throws the lower end of said lever to the right side 60 of the cam track 40, which latter is engaged

by the anti-friction roller 50, which has the effect of forcing the lower end of said lever outwardly or to the right and the unseating of the valve 32, in which position it remains long enough to permit a charge of 70 carbonated water to enter and fill the bottle. Just previous to this the neck of the bottle has been clamped into the lower end of the filling head by means of the rubber ring 41. This ring is held in a cap 42 mounted on the 75 lower end of the filling head just below the annular metal flange 43 between which and the cap the rubber is adapted to be compressed whereby to form an air-tight connection with the neck of the bottle at a 80 point below the bead. This compression is accomplished by means of a pair of bell crank levers 44, 44, pivoted at 45 at each side of the filling heads. From the shorter ends of these bell-crank levers, links 46 extend to studs 47 on the cap 42. The upper end is preferably provided with the anti-friction roller 48 which engages a cam rail 49 whereby the lever is swung to the left, in the direction indicated by the arrow, thus 85 lifting the cap 42 and compressing the rubber ring 41 about the neck of the bottle. In this way the leakage of gas or liquid is precluded. Of course it is understood that the operation just described is accomplished 90 by the wheel 4 which supports the filling head, arriving at a dip in the track 3, as the filling heads move vertically as well as in a circular orbit, whereas the bottles travel beneath several of them during a portion of 95 their circuit.

As the capping of each bottle is performed as soon as practicable after filling the bottle, the mechanism for capping will now be described.

100 A hopper 51 is preferably supported on a vertical column 52 from the base of the machine and from this a chute 53 leads to a position over the path of the cap pins 54. A cup 55 is mounted on each cap pin 105 54, where it is yieldingly supported by a spring 56. This cup is provided with two upwardly projecting ears 57, 57, adapted to strip one cap at a time from the lower end 110 of the chute 53. The outlet of the chute 115 at the lower end may be in various forms, only two of which I have disclosed, one in which slots 58, 58, extend longitudinally thereof in position to receive the ears 57, 57, whereby one cap is stripped from the 120 end of the chute at a time and caught by the cup 55. In this form, the mouth, shown in Fig. 11, is slightly constricted as at 60 to prevent a perfect cap from dropping out, while admitting of an imperfect or undersized cap dropping out by gravity. In the other form shown in Fig. 12, the slots 58 extend transversely of the chute instead of longitudinally. The object and advantage 125 of the first form is that it will allow an 130

- under-sized cap to drop out. Each cap pin is held on a slide 61. There are as many of these cap pins and slides as there are filling heads, one being located opposite or 5 adjacent to each filling head during a portion of their travel and under the filling head during the remaining portion of travel. This is accomplished by means of the double oval cam 62 shown in Fig. 3.
- 10 Each slide is provided with a projection 63 which engages the depending flange 64 of the double oval cam which these projections follow, whereby the position of the cap pins is automatically regulated. In other words,
- 15 while the filling heads travel in a circular path, the cap pins travel in and out of said circular path, so that they reach a point in alinement with their corresponding filling heads, when the filling head is receiving 20 a cap, and they move out of alinement therewith preceding and preparatory to the operation of filling the bottle.

Referring back to the hopper 51, it is provided with a channel 80 which leads to 25 the chute 53, said channel being adapted to receive the stoppers and feed them to the chute when they fall thereinto in the proper position. This channel has a groove in the bottom of one edge large enough 30 to receive the flange of the cap. A sweep 82 comprising one or more arms is adapted to remove any caps from the channel as it rotates in contact with them, which are not perfectly placed and alined therein as 35 they project sufficiently above the channel to fall into the path of the sweep when not perfectly alined.

Following the path of the cam 62, each capping pin is finally moved out to a position 40 directly beneath its corresponding filling head as shown at the left of Figs. 1 and 2. At this period the wheel 4 of the filling head above the cap pin reaches a dip in the track, thus forcing the cup 55 down 45 and the flaring edge of the cap past the inner surface of the ring 65. This ring 65 is held in position just beneath the capping cone 66, and rigidly against the latter by means of the screws 67, the inner ends of 50 which taper as at 69 whereby to hold the ring rigidly seated. Here the cap is held until the filling heads thus supplied with caps and prepared, travel perhaps a quarter revolution to a point where a bottle passes 55 beneath them, when the wheel 4 reaches another dip in the track, forcing the filling head down until the mouth of the bottle has reached the cap and the edges of the cap are forced against the converging walls of 60 the capping cone 66, by which means they are bent securely around and beneath the bead at the mouth of the bottle. This is accomplished just after the filling of the bottle and before the filling head is lifted 65 therefrom. The capping cone 66 is held be-

tween lugs 68, 68, and the screws 67, 67, grooves being formed back of the cone for any liquid which may splash up into the filling head to drain down outside of the cone into the bottle.

70 The parts are rotated by means of a traveling conveyer which not only drives the mechanism but which also conveys the bottles through this machine which likewise has carried them from a washing machine 75 to the machine herein described and from this machine carries them to a labeling machine without their being handled. This conveyer is composed of trucks 70, each preferably having three flanged wheels 71, 80 71, which travel on tracks 72, 72. Depending from these tracks are the sprocket chain links 73 which latter engage the sprocket teeth 74 on the outer surface of the rotatable sleeve 85 whereby to transmit motion thereto. 85 Four standards 86 extending from this sleeve to the top of the machine, support a plate 87 at the top, which latter in turn supports the filling apparatus.

To briefly review the operation; the bottles 90 are carried into the machine by the conveyer to which they are securely clamped. A cap is fed to the cap pin as shown at the right hand side of Fig. 2, the cap pin at this point being out of the path of the bottle. The 95 valve which controls the supply of carbonated liquid is controlled by the bottle to be filled, and just previous to the time the bottle is filled and the filling head is lifted from the bottle by arriving at a more elevated portion on the track, the valve closes and shuts off the supply, the neck of the bottle being released and the bottle being still held securely in the conveyer. During the operation of the filling, over on the opposite side 100 of the machine the cap pins have come into line with the filling heads and the filling heads successively move downwardly to receive a cap from a cap pin, after which they rise upon the track and travel upon the elevated portion of the latter until they reach the point where the capping takes place. 105 Thus the cap pins in turn move in and out of alinement with the filling heads. When 110 in alinement, the filling heads descend to receive a cap; when out of alinement, one cap pin at a time receives a cap, while several bottles at a time are being filled with the liquid. Thus the operation continues 115 automatically from start to finish, the caps being fed, inserted into the filling heads, the bottles being filled, valves opened and closed, and caps applied to the bottles by various automatic operations of the machine.

120 From the foregoing it will be noticed that both the cap pins and the conveyer travel around the machine in a horizontal plane, but that the filling heads while traveling in a circular orbit also rise and dip, that is 125 to say, they rise away from the cap pins and 130

bottles, and they also at predetermined intervals receive a cap as well as the mouth of a bottle.

It is evident that more or less slight changes might be resorted to in the form and arrangement of the several parts described without departing from the spirit and scope of my invention, and hence I do not wish to limit myself to the exact constructions herein set forth, but:—

- Having fully described my invention, what I claim as new and desire to secure by Letters Patent, is:—
1. In a bottling machine, a plurality of bottle filling heads, means for causing the latter to travel in a circular direction, and a plurality of cap pins, which have an eccentric rotary movement in and out of alignment with the filling heads.
  2. In a bottling machine, a plurality of bottle filling heads, means for causing the latter to travel in a circular direction, means for imparting an upward and downward undulatory motion to said heads, and a plurality of cap pins which have an eccentric rotary movement in and out of alignment with the filling heads.
  3. In a bottling machine, a plurality of filling-heads, a bottle conveyer adapted to contain bottles, a plurality of cap pins, all of said parts moving continuously and automatically so that each cap pin moves in and out of alignment with a filling head.
  4. In a bottling machine, cap pins and filling heads, said filling heads traveling in a circular orbit, means for causing the filling heads to rise and fall at predetermined periods, and the cap pins traveling in an eccentric orbit in and out of the path of the filling heads.
  5. In a bottling machine, cap pins and filling heads, said filling heads traveling in a circular orbit, means for causing the filling heads to rise and fall at predetermined periods, the cap pins traveling in an eccentric orbit in and out of the path of the filling heads, and means for successively feeding caps to each cap pin.
  6. In a bottling machine, the combination with a base, a superstructure supported thereon, of an undulating track supported by the superstructure, wheels thereon, filling heads supported by the wheels and caused to rise and fall by the travel of the wheels upon the track, and a conveyer which carries the bottles to be filled, and which transmits motion to the moving parts of the machine.
  7. In a bottling machine, the combination with a base, a superstructure supported thereon, of an undulating track supported by the superstructure, wheels thereon, filling heads supported by the wheels and caused to rise and fall by the travel of the wheels upon the track, a conveyer which carries the

bottles to be filled, and which transmits motion to the moving parts of the machine, said conveyer comprising trucks, cups for the bottles, and a sprocket chain adapted to engage the sprocket teeth on the machine for transmitting motion thereto.

8. In a bottling machine, a plurality of filling heads and cap pins, they corresponding in number, a circular undulating track, the filling heads traveling on said track in a rotary undulating path and the cap pins in a horizontally irregular path in and out of the path of the filling heads.

9. In a bottling machine, the combination with a base and superstructure, and an undulating circular track supported on the superstructure, of filling heads, rods by which the filling heads are supported, wheels mounted on the track reciprocating the rods thereon, hangers extending from the rods to the wheels, and means for imparting a rotary motion to the moving parts of the machine.

10. In a bottling machine, the combination with a base and superstructure, and an undulating circular track supported on the superstructure, of filling heads, rods by which the filling heads are supported, a header and guide through which the rods slide, wheels mounted on the track, hangers extending from the rods to the wheels, means for imparting a rotary motion to the moving parts of the machine, and cap pins which move radially around an irregular guide in and out of alignment with the filling heads.

11. In a bottling machine, the combination with a base and superstructure, and an undulating circular track supported on the superstructure, of filling heads, rods by which the filling heads are supported, a header and guide through which the rods slide, wheels mounted on the track, hangers extending from the rods to the wheels, means for imparting a rotary motion to the moving parts of the machine and cap pins which move radially around an irregular guide in and out of the vertical path with the filling heads.

12. In a bottling machine, the combination with a base and superstructure, and an undulating circular track supported on the superstructure, of filling heads, rods by which the filling heads are supported, a header and guide through which the rods slide, wheels mounted on the track, hangers extending from the rods to the wheels, means for imparting a rotary motion to the moving parts of the machine, cap pins which move radially around an eccentric in and out of alignment with the filling heads, and means for supplying a cap to one of the pins while out of the path of the filling heads.

13. In a bottling machine, a filling head having a threaded orifice in its upper end, a

plug adapted to screw into this orifice, said plug having a threaded orifice and a threaded rod which screws into said orifice for varying the capacity of the filling head without changing its elevation.

14. In a bottling machine, a filling head having a threaded orifice in its upper end, a plug adapted to screw into this orifice, said plug having a threaded orifice and a threaded rod which screws into said orifice for varying the capacity of the filling head without changing its elevation, lock nuts 10 turning on said threads and a packing between the filling head and the adjacent lock 15 nut.

15. In a bottling machine, the combination of a filling head, plug, and rod, the filling head having a threaded orifice adapted to receive threads on the plug, and the plug 20 having threaded orifices adapted to receive threads on the rod whereby the capacity of the filling head may be varied by turning the plug without altering the elevation of the filling head.

25 16. In a bottling machine, the combination with a filling head, an elastic ring at the mouth thereof, means for automatically compressing the ring about the mouth of the bottle to be filled, said means consisting 30 of a cup mounted to slide on the end of the filling head, levers pivoted to the sides of the filling head, links extending from the levers to the cup, and a cam rail in position to be engaged by the levers at intervals whereby to raise the cup and compress the ring.

35 17. In a bottling machine, the combination with a filling head, means for supplying liquid thereto, of a valve, and means for automatically opening the valve when a bottle 40 is in position to be filled, said means consisting of a spring actuated valve rod, a

valve operating lever, a trip lever connected therewith and in position to be operated by the bottle, and a cam track in position to be engaged by one end of the valve operating 45 lever.

18. In a bottling machine, the combination with a rotary header having an annular channel therein, a main pipe and swivel, and branch pipes leading from the swivel 50 to the header, of filling heads and hose extending from the header to the filling heads.

19. In a bottling machine, the combination with a rotary header having an annular channel therein, a main pipe and swivel, and branch pipes leading from the swivel to the header, of filling heads and hose extending 55 from the header to the filling heads, and automatic means for controlling the discharge into the bottle.

20. The combination with a cap-finger carrying stripping means, of a cap-chute having transverse slots therein in the path of the stripping means through which the latter pass to rake a single cap at a time 60 65 from the chute.

21. The combination with a rotary table, a slide slidably mounted therein, and a cap-finger carried by the slide, of a cap-chute having transverse slots therein, and a cap-finger carrying means located at the upper 70 end thereof in position to pass through the slots in the cap-chute as the table rotates for the purpose of raking a cap transversely 75 from the chute on to the end of the cap-finger.

In testimony whereof I affix my signature in presence of two witnesses.

SAMUEL KAYE.
